UNITED STATES PATENT OFFICE

165,488

TOY AUTOMOBILE

Harry Sebel, London, England

Application March 14, 1950, Serial No. 8,530

Term of patent 14 years

(Cl. D34—15)

To all whom it may concern:

Be it known that I, Harry Sebel, a subject of the King of Great Britain, residing in London, England, have invented a new, original, and ornamental Design for a Toy Automobile, of which the following is a specification, reference being had to the accompanying drawings, forming part thereof.

Fig. 1 is a front perspective view of a toy automobile, showing my new design;

Fig. 2 is a bottom plan view;

Fig. 3 is a side elevational view; and

Fig. 4 is a top plan view.

I claim:

The ornamental design for a toy automobile, as shown.

HARRY SEBEL.
